UNITED STATES PATENT OFFICE.

HERBERT C. DRUMM, OF CANTON, OHIO, ASSIGNOR TO THE UNION METAL MANUFACTURING COMPANY, OF CANTON, OHIO, A CORPORATION OF OHIO.

HANDLE FOR FOUNDRY-FLASKS.

1,335,565.

Specification of Letters Patent. Patented Mar. 30, 1920.

Application filed July 11, 1919. Serial No. 310,058.

To all whom it may concern:

Be it known that I, HERBERT C. DRUMM, a citizen of the United States, residing at Canton, in the county of Stark and State 5 of Ohio, have invented a new and useful Handle for Foundry-Flasks, of which the following is a specification.

This invention relates to improvements in handles for rolled or pressed steel foun- 10 dry flasks.

The objects of the invention are to pro- 15 vide a handle formed of sheet metal, to form the handle in a minimum of operations from a single sheet and to generally improve and

15 simplify constructions of this character.

With these objects in view the invention 20 consists in the novel construction and ar- 25 arrangement of parts, hereinafter described, illustrated in the accompanying drawings, and particularly pointed out in the appended 25 claims, it being understood that various changes in the form, proportions, size and minor details of construction may be made 30 within the scope of the appended claims, 35 without departing from the spirit or sacri- 40 ficing any of the advantages of the invention.

The invention thus set forth in general 35 terms is illustrated in the accompanying 40 drawings forming part hereof, in which—

Figure 1 is a perspective view of a portion 45 of a rectangular flask showing the im- 50 proved handle attached thereto;

Fig. 2 is a plan view of the blank from 55 which one of the handles is formed;

Fig. 3, a plan view of the blank after 59 the first stamping operation;

Fig. 4, a side elevation of the same;

Fig. 5, a plan view of the finished handle; 40 and

Fig. 6, is a perspective view of a portion 45 of a rectangular flask showing the type of 50 handle designed for flasks of large size.

Fig. 7 is a perspective view of a portion 55 of a circular flask showing the handle designed 60 for use upon the circular flasks.

Fig. 8 is a plan view of the blank from 65 which this handle is made; and

Fig. 9 is a side elevation of the handle 70 used upon the circular flask.

A practical embodiment of the invention 75 is disclosed in the accompanying drawings, forming a part of this specification in which similar numerals of reference indicate cor-

responding parts throughout the several 55 views.

The numeral 1 indicates the rectangular blank of sheet metal of proper gage from which the handle is stamped and the numeral 2 indicates generally the product of 60 the first stamping operation. With this operation the central corrugation 3 is formed in the attaching portion 4 of the handle while the metal at the other end of the blank from which the hand grip is formed is bent 65 upwardly into channel form as shown at 5, this hand grip portion being off-set as shown at 6.

With the next operation the tubular hand 70 grip 7 is completely formed and the finished 75 handle as illustrated in Fig. 5 is punched with a plurality of apertures 8 which receive rivets 9 or their equivalents by means of which the handles are attached to the corners of the corrugated flask 10. 75

As shown in Fig. 1 the corrugated rib 3 engages one of the spaced corrugations 11 formed upon the blank, thus adding to the 80 rigidity of the connection. The hand grip 7 being off-set from the attaching portion 80 4 of the handle obviates any obstruction from extending out from the sides of the flask, thus forming a neater and more practical construction.

In Fig. 6 is illustrated a modified form of 85 the handle adapted for use upon large flasks, the handle being provided with a plurality 90 of corrugated ribs 12 which engage adjacent corrugations 11 upon the flask. In this construction of handle, the hand grip 7' is 95 formed in the same manner as in the form illustrated in Figs. 1 to 5, inclusive and is off-set from the attaching portion as shown at 6' the only difference in the construction 95 of the handle being the provision of the plu- 95 rality of corrugated ribs 12.

In Figs. 7 to 9 inclusive is illustrated an attachment of the handle for use upon curved or circular flasks. This handle is formed from a tapered blank 13 provided 100 with the upper and lower concave and convex edges 14 and 15 respectively, the side edges of the blank being tapered toward the top and provided with the cut-out portions 17 near the bottom, a centrally disposed slot 105 18 being provided in the bottom edge of the blank, said slot being of the same length as the cut-out portions 17. The lower end of

the blank is thus divided by the slot 18 into two equal portions 19.

In forming the handle the portion of the blank above the slot 18 and the cut-out portions 17 is pressed into the tubular hand grip 20, the portions 19 being bent in a plane at right angles to the axis of said conical hand grip forming the attaching flanges 21, the edges of these flanges adjacent the upper 10 ends of the cut-out portions 17 and the slot 18 being bent upwardly forming a semi-circle 22 adapted to fit over one of the corrugations 23 upon the curved flask 24. Attaching rivets or their equivalents 25 are 15 provided for connecting the flanges 21 to the flask.

Although the drawings and above specification disclose the best mode in which I have contemplated embodying my invention 20 I desire to be not limited to the details of such disclosure, for, in the further practical application of my invention, many changes in form and construction may be made, as circumstances require or experience suggests, 25 without departing from the spirit of the invention, within the scope of the appended claims.

I claim:

1. A flask handle formed from a sheet 30 metal blank having a longitudinal slot ex-

tending from its lower edge to a point intermediate its ends, the portion of the blank above the slot being bent into tubular shape forming a hand grip and the portions upon each side of the slot being bent outwardly 35 in opposite directions to form attaching flanges.

2. A flask handle formed from a tapered sheet metal blank having a concaved upper edge and a convex lower edge and a longitudinal slot extending from the convex edge to a point intermediate the ends of the blank, the portion above the slot being bent into tubular shape forming a frusto-conical hand grip and the portions upon each side 45 of the slot being bent outwardly in opposite directions forming attaching flanges.

3. In combination with a flask provided with a convex rib, a handle formed from a sheet metal blank, one end of said blank being bent into tubular shape forming a hand grip, the other end of the blank forming an attaching portion provided with a concaved portion to receive the rib upon the flask, and means for connecting said handle to the 55 flask.

In testimony that I claim the above I have hereunto subscribed my name.

HERBERT C. DRUMM.
